UNITED STATES PATENT OFFICE.

EMMERICK ANDERSON, OF DAYTON, KENTUCKY.

SHOE.

Application filed March 7, 1924. Serial No. 697,656.

My invention relates to improvements in turned shoes, and more particularly to the provision of a stiff shank and support for shoes of the turned shoe type.

The turned shoe is less expensive than the welt shoe and is often used in light slippers for women and children. In its manufacture the upper is stitched to the sole and then turned inside out, after which the shoe is completed in the manner common to all shoes. The sole is usually light and the upper thin and flexible, and the process of manufacture is such that heretofore, so far as I am advised, no shank stiffener and arch supporter has ever been incorporated in this style of shoe.

It is my object to provide for such reinforcement and stiffening and to do so in an economical manner, without interfering with the usual processes of manufacture, and without requiring any special shaping of the shoe, so as to depart from its graceful lines.

In ladies' thin shoes the shank is usually very narrow, leaving a considerable overhang of the upper at the inside of the foot, and one of my objects is to protect and support this overhanging portion without interfering with the lines of the shoe in any way.

I accomplish my objects by that certain construction and arrangement of parts to be hereinafter more specifically pointed out and claimed.

In the drawings:

Figure 1 is a plan view of a shoe looking down upon it, with the lining pulled away to expose the shank and arch stiffener.

Figure 2 is a perspective view of the shank piece and stiffener attached to a fragment of the shoe sole.

Figure 3 is a larger perspective view of the shank assembly shown in Figure 2 as viewed from the underside, with the pocket for the arch supporting tongue cut away.

Figure 4 is a sectional view taken along the line 4-4 in Figure 1.

In making a turned shoe the sole is tacked onto the last with the grain toward the last. The shoe is then lasted with the lining out and the grain of the leather toward the last. The shoe is then sewed, the last pulled out and the shoe turned. The arch supporting device hereinafter described is then placed within the shoe and the shank, to which a pocket and arch supporting metallic piece is

secured, is then given the second lasting on the last for the opposite foot. Following this operation the shoe is ready for the further steps of smoothing up and seating in the usual way.

My novel device is formed of a piece of stiff material 1, such as leather formed in the shape of the shank portion and heel portion of a sole for the exact shoe in question. Stitched to the inner underneath edge 2 of the piece is another portion of fairly stiff material such as leather 3, which is so cut that when stitched to the edge of the piece 1, it will follow the outlines of the portion of the upper where it overhangs the sole of the shoe, at the shank thereof. This piece 3 curves down at the two ends of the shank, so that at the ball and at the heel, it does not interfere with the fit of the shoe. It is shaped to present a convex curve to the inside of the shoe, both in direction of length of the shoe and in direction of height thereof. In other words, it is shaped so that when sewed onto the shank piece of leather, it will have a somewhat spherical contour tapering to the ball and heel ends of the shank, so as to take care of substantially all of the overhang of the upper at the inside of the shank.

In order to stiffen this element formed of pieces 1 and 3, I provide a single metallic shank piece. This piece has the usual body portion 4, which curves slightly to conform to the slope of the sole of a shoe, and it has a tongue 5, extending upwardly from the body portion at about the middle of the inside edge thereof, at a general angle of say twenty degrees.

The tongue 5 is not of the full width of the piece 3 of the arch supporting element of the shank, but is considerably less wide, thereby limiting the unyielding area of the piece 3, and giving it a slight yield at both sides of the greatest overhang of the upper. Also this relatively small dimension in width permits of one size of shank piece being used in a wide variety of sizes of shoe, which is a manufacturing advantage that will be obvious.

To hold the tongue 5 and piece 3 together I adopt the following preferred expedient. I stitch to the bottom side of the piece 3 a pocket forming piece of fabric 6. The piece 6 is not secured to the body 1 of the shank piece and thus leaves a pocket mouth into which the metal tongue 5 can be inserted.

After insertion of the tongue, some suitable cement is used to paste down the piece 5 to the bottom of the shoe.

In setting the entire piece so made up into 6 the shoe, the portion 1 is set over the sole of the shoe, within the shoe, after it has been turned, and held in place by means of a screw or rivet.

In securing the metal shank piece to the 10 leather portion 1, certain rivets 7 are shown. The rivets are set through the leather and the metal. One or more of these rivets as at 9, can be made long enough to pass through the sole of the shoe, and are hammered over on the underside of the shank portion of the sole.

A shoe so formed, will provide adequate support for the foot, since the leather itself, being held without flexibility along its lines 20 of greatest strain, will fully sustain the foot, and yet will have enough give away from the metal itself to shape itself to the peculiarities of the foot of the wearer. It need not be molded specially for each shoe, for 25 this reason, prior to being set in place, and

the second lasting operations will cause it to take the shape of the last, so that the wearer has no discomfort not resulting from the last itself.

The lining 8 is cemented in place after the 30 reinforcement is in the shoe.

Having thus described my invention, what I claim as new and desire to secure by Letters Patent, is:—

A turned shoe comprising in combination 35 a sole with a shoe upper lasted to the sole, a shank piece secured in the shoe, a pocket formed of a stiffening member secured at its lower edge to the under edge of said shank piece and a complementary flexible portion 40 secured at all of its edges to the stiffening member excepting at its lower edge thereby forming an inverted pocket, and an arch supporting plate having a tongue extending into 45 said pocket, said plate secured to the under surface of said shank piece, and said shank piece and plate secured to said sole with rivets extending through said shank piece, plate and sole.

EMMERICK ANDERSON.
